(57) **CLAIM**

We claim the ornamental design for a liquid spray bottle, as shown and described.

DESCRIPTION

FIG. 1 is a front, side and rear elevation view of the new design;

FIG. 2 is a top perspective view thereof;

FIG. 3 is a bottom perspective view thereof;

FIG. 4 is a top view thereof, shown at an enlarged scale;

FIG. 5 is a bottom view thereof; and,

FIG. 6 is a perspective view thereof.

The broken line graphical elements are for illustrative purposes only and form no part of the claimed invention.
